DESIGN FOR A PAPER NAPKIN

Robert B. Stevens, Greenwich, N. Y., assignor to Stevens & Thompson Paper Company, Greenwich, N. Y., a corporation of New York

Application November 9, 1944, Serial No. 116,238

Term of patent 14 years

(Cl. D59—2)

To all whom it may concern:

Be it known that I, Robert B. Stevens, a citizen of the United States, residing at Greenwich, county of Washington, and State of New York, have invented a new, original, and ornamental Design for a Paper Napkin, of which the following is a specification, reference being had to the accompanying drawing, forming a part thereof. The drawing is a plan view of my napkin; the outline of the napkin and the surface ornamentation on one quarter thereof being illustrated; it being understood that the ornamentation is the same in each quarter.

I claim:

The ornamental design for a paper napkin, as shown and described.

ROBERT B. STEVENS.
